UNITED STATES PATENT OFFICE.

EMMA A. PLUMMER, OF NEW YORK, N. Y.

BATHING-SUIT.

1,082,905.

Specification of Letters Patent. Patented Dec. 30, 1913.

Application filed June 27, 1912. Serial No. 706,161.

To all whom it may concern:

Be it known that I, EMMA A. PLUMMER, a citizen of the United States, residing in the city of New York, borough of Brooklyn, 5 county of Kings, and State of New York, have invented certain new and useful Improvements in Bathing-Suits, of which the following, taken in connection with the accompanying sheet of drawings, forms a full, 10 clear, and concise description.

One of the objects of my invention is to produce a one-piece bathing suit made up of united waist and skirt portions, the skirt portion being of the divided type and so 15 constructed that the folds thereof will dispose themselves gracefully around the limbs of the wearer, giving the appearance of the regulation full skirt.

A further object of my invention is to provide a bathing garment so constructed that when in use the skirt will remain in draped position and not ride up around the body of the wearer, and these objects are attained without in any way interfering with the 25 free action of the limbs of the wearer during bathing or swimming.

Referring to the accompanying sheet of drawings in which I have illustrated one preferable embodiment of my invention, 30 Figure 1 illustrates a garment made in accordance therewith, showing the uniformity of the folds when the garment is worn. Fig. 2 is a side view, partly in section, illustrating the dividing portion of the garment. Fig. 3 35 is a diagrammatic illustration of the pattern used to form the division. Fig. 4 is a view taken on line 4^a-4^a of Fig. 2.

In detail, the numeral 1 indicates the waist portion of the garment which is provided 40 with a suitable opening in the front at 1' to enable the wearer to don the same.

2 indicates the skirt portion which is preferably fixedly united with the waist portion at 3 so as to form a single garment. At a 45 point substantially below the horizontal median line of the skirt portion, the front and rear thereof is slit or bisected and an inverted V-shaped piece 4, of the shape of the pattern, is inserted and sewed to the 50 edges, forming a double dividing wall to produce in the garment a lower trunk portion.

The partition forming the lower portion of the skirt into separate limb or trunk portions extends but a short distance above the 55 knee and some distance below the crotch of the wearer so as to allow freedom of leg movement and is of sufficient length to prevent the garment from rising and exposing the limbs of the wearer. The inverted 60 V-shaped partition 4 may be made of a single piece or two pieces joined together at the upper edge 6. The edges are preferably curved or scalloped as shown, the lower edges 7 being so to a greater degree in order 65 to prevent it from becoming exposed below the skirt 2 in case of any sagging due to weight when wet or other causes. The upper edge of the insert is made concave, that is, is higher at the front and back where it is 70 attached to the skirt, than it is in the middle so that it will pass considerably below the crotch of the wearer. The width of the partition is considerably less than the width of the skirt so that the point of connection between the two will be well within the general compass of the skirt when draped upon 75 the wearer. By this the lower part of the skirt at the point of connection is drawn inwardly and gives an appearance to the skirt 80 of being an ordinary plaited skirt, making invisible the bisected feature of the garment.

The skirt is made very full and is preferably plaited, the plaits, indicated at 5 being sufficiently numerous to present, when 85 draped on the body of the wearer, a harmonious appearance both front and back, so that it will appear from the foregoing that I provide a garment of the divided type which, owing to its fullness, conceals 90 and hides from view the bisected feature, giving the appearance of the regulation bathing skirt.

Having thus described my invention, what I claim as new herein and desire to secure 95 by Letters Patent is:

1. A short skirt for a bathing suit or the like, bisected at and near its lower extremity only, by a transverse partition extending from the front to the rear of the skirt, the upper edge of said partition lying considerably below the crotch of the wearer, the short leg portions thus formed being open at the bottom and arranged to fall freely about the 100 limbs of the wearer.

2. As a new article of manufacture, a skirt opened at the bottom and adapted to fall freely about the limbs of the wearer, said skirt being provided with a folded insert bisecting the same at its lower extremity, 110 the folded edge extending beneath the crotch of the wearer and the side edges of the insert being secured to the skirt along each side of the line of bisection of the front and rear thereof, thereby producing two leg portions opened at the bottom, said leg sections being of a sufficient fullness to render the line of bisection invisible when the skirt is worn.

3. As a new article of manufacture, a skirt open at the bottom and arranged to fall freely about the limbs of the wearer, an insert therefor adapted to bisect the same at its lower extremity to produce two leg portions, each open at the bottom, and of sufficient fullness to render the line of bisection invisible when the skirt is worn, said insert being secured to the front and back portions of the skirt, the upper edge of the insert being concave so that the central portion thereof is considerably below the crotch 20 of the wearer.

4. A skirt for bathing suits and the like, bisected at and near the bottom only and having a folded insert extending from the front to the rear thereof, the side edges of said insert being secured to said skirt along each side of the lines of bisection of the front and rear thereof, the lower edges of said insert being upwardly curved or scalloped.

5. A skirt for bathing suits and the like, bisected at and near the bottom and having a folded insert extending from the front to the rear thereof, the folded edge of the insert being concave and passing under the crotch of the wearer and the side edges of the insert converging toward the bottom so that the insert is shorter at the bottom than at the top, said side edges being secured to said skirt along each side of the lines of bisection of the front and rear thereof.

In witness whereof I have hereunto set my hand in the presence of two subscribing witnesses.
